UNITED STATES PATENT OFFICE.

SETH A. WELLMAN, OF MASON CITY, IOWA.

VENTILATING MEANS.

1,335,948.

Specification of Letters Patent. Patented Apr. 6, 1920.

Application filed November 14, 1918. Serial No. 262,466.

To all whom it may concern:

Be it known that I, SETH A. WELLMAN, a citizen of the United States of America, and resident of Mason City, Cerro Gordo county, 5 Iowa, have invented a new and useful Ventilating Means, of which the following is a specification.

The object of this invention is to provide improved means for supplying ventilation in and between rooms of a building.

A further object of this invention is to provide improved means for supplying ventilation between rooms of a building when the communicating door is closed, such 15 means being effective both at the top and bottom of the door so that fresh air may enter and foul air escape.

A further object of this invention is to provide improved means for supplying ventilation to a room when the door thereto is closed, such means being effective at both 20 the top and bottom of the door so that fresh air may enter and foul air escape, means also being provided for suspending ventilation 25 at times.

A further object of this invention is to provide improved means for ventilating a room when the door thereto is in closed position, by providing spaces between upper and 30 lower margins of said door and the adjacent frame members, means also being provided for automatically closing such spaces at times when the door is closed, to suspend the 35 ventilating function, and for opening said spaces when the door is opened.

A further object of this invention is to provide means for ventilating a room when the door is in closed position, by providing spaces between upper and lower margins of 40 said door and the adjacent frame members, shutters being hinged to said frame members and adapted to close said spaces at times to suspend the ventilating function; means also being provided for automatically moving 45 said shutters to closing position when the door is closed and to horizontal or open position when the door is opened.

My invention consists in the construction, arrangement and combination of elements 50 hereinafter set forth, pointed out in my claims and illustrated by the accompanying drawing, in which—

Figure 1 is an elevation, partly in section,

illustrating a door, in closed position, equipped with my improved ventilating devices, such devices being in position for suspending the ventilating function. Fig. 2 is a horizontal sectional view on the line 2—2 of Fig. 1, on an enlarged scale. Fig. 3 is a detail vertical section, on a further enlarged 55 scale, taken substantially on the line 3—3 of Fig. 2, a portion of the section being on another plane to illustrate certain details of construction. Fig. 4 is a plan, partly in section, illustrating the devices for holding the threshold shutter in horizontal position, the door being omitted. Fig. 5 is a cross-section on an enlarged scale on the indicated line 60 5—5 of Fig. 4.

In the construction of the devices as shown 70 the numeral 10 designates a door hinged at one side margin to a jamb 11 and adapted to be closed against a stop 12 carried by the opposite jamb 13. The door 10 is of materially less length than the vertical space between the floor 14 and head casing 15, being spaced at its lower margin from said floor and at its upper margin from the header 16, thus providing lower and upper ventilating 75 spaces through which fresh air may enter the room to which said door communicates, and foul or heated air may escape; this provision being especially desirable where vacuum or pipeless heating systems are employed. My invention relates primarily to means for suspending the ventilating function at times, 80 by means of hinged shutters automatically operated to closing position relative to the ventilating spaces when the door is closed and to horizontal position when the door is 85 opened, for a purpose hereinafter made clear; such devices also including means for holding said shutters in horizontal position at times irrespective of the position of the door, when it is desired to render the ventilation 90 effective.

The numeral 17 designates a rigid threshold member mounted on the floor 14 between the jambs 11, 13 but not extending beneath the door 10. A movable threshold 100 member 18, which may be called a threshold shutter, is hinged at one margin to the rigid threshold 17 and articulates on a transverse line substantially in the plane of the inner margin of the closed door, 105 such line being indicated by the numeral

19 in Fig. 4. The rigid and hinged threshold members may be beveled at their outer marginal portions in a common manner, as shown in Fig. 3, and together compass the 5 space between the jambs 11 and 13, when said hinged member is in horizontal position. When the hinged threshold member or threshold shutter 18 is in vertical position, which should occur only when the door 10 is closed, it fills the space beneath said door and is substantially in the same vertical plane, as shown in Fig. 3 in solid lines. One of the hinges employed for securing the threshold shutter 18 to the rigid threshold 17 is shown in detail in Fig. 5, and comprises a hinge member 20 fixed to and in 10 the same horizontal plane as said rigid member, and a hinge member 21 fixed to the end of the threshold shutter, said members being 15 pivotally connected by a hinge pin 22. The hinge member 21 is formed with a tongue 21^a extending within a fork of the hinge member 20 and the extremity of said tongue is rounded and spaced from the end of the 20 fork. A flexible hanger or strap 23 is fixed 25 at one end to the upper surface of the tongue 21^a, as by a tack or screw 24, extends over the rounded end of said tongue and through the space between it and the fork of the 30 other hinge member, through a hole 14^a in the floor, and has a weight 25 fixed to its depending end portion. The weights 25, one at each end of the threshold shutter, tend to overbalance said member and hold 35 it in vertical or closing position.

An upper shutter 26 is hinged at one margin, in any suitable manner, to the header 16, and is adapted to fill the ventilating space at the upper margin of the door 10. The upper shutter 26 tends by gravity 40 to remain in depending vertical or closing position, in the same vertical plane as the closed door.

A shutter moving arm is pivoted at one 45 end by a screw or bolt 27 to the upper face of the rigid threshold 17, adjacent the jamb 11 and also adjacent the line of articulation of the threshold shutter 18. The shutter moving arm comprises a horizontal portion 50 28 resting upon the threshold 17; a vertical portion 29 integral with and rising from the free end of said horizontal member and preferably connected therewith by a slightly curved portion; a relatively short horizontal portion 30 extended laterally from the end of the vertical portion and extending beneath and in close contact with the bottom of the door 10; and an upstanding lug 31 55 on the end of said short horizontal portion, and located on the opposite side of the door from the pivot 27. A latching bar 32 is pivoted at one end by a screw or bolt 33 to the lower margin and on the outer face of the door 10 and is offset slightly away from

said door throughout the major portion of 65 its length, thus providing a space between it and the door into which the lug 31 of the shutter moving arm is received and adapted for a restricted sliding movement as the door is moved on its hinges. Thus 70 means is provided for operatively connecting the door to the threshold shutter.

A similar shutter operating arm, designated generally by the numeral 34, is provided for the upper shutter 26, and is hinged 75 to the header 16, passes across the top of the door and has a lug engaging between said door and a latching bar 35 pivoted at the upper end of the door, thus providing means 80 for operatively connecting the door to the upper shutter.

A lever 36 is pivoted between its ends on a screw or bolt 37 near the vertical center of the door 10 and substantially midway between and in vertical line with the latching 85 bars 32 and 35. Links 38, 39 are connected at their ends to the lever 36, on opposite sides of the fulcrum 37 thereof, and extend in opposite directions and are pivotally connected at their opposite ends to the latching 90 bars 32 and 35 respectively. The lever 36 is preferably provided with a handle 40 for manual operation thereof.

In use, the parts being arranged as shown and described, the shutters 18 and 26 will 95 normally remain in vertical or closing position, and fill the ventilating spaces at the bottom and top of the door and suspend the ventilating function. It is undesirable to permit the shutters to remain in such position except when the door is closed, especially the threshold shutter 18, as it would form an obstruction between the door jambs, and it is for this reason, in part, that the shutter moving arms are provided. When 100 the door 10 is moved to open position, pressure is applied to the lugs 31 of said arms and the arms are operated across the lines of articulation of the shutters, the vertical portions 29 of said arms engaging the inner 110 faces of the shutters and, through continued movement of said door, moving said shutters to their horizontal positions. With respect to the lowermost arm, this has the effect of 115 positioning the threshold shutter 18 flat on the floor 14 and in the same horizontal plane as the rigid threshold member 17, thus providing a normal threshold between the lower ends of the jambs and permitting free walking or moving of articles through the doorway. It is to be understood that in this 120 position the longer or lower horizontal arm 28 of the shutter moving arm engages the upper surface of the threshold shutter and holds it in the horizontal position above described, while the upper arm 34 holds the upper shutter 26 in a similar position. Closing movement of the door, when carried to

completion, carries the shutter moving arms out of engagement with the shutters and permits them to assume the vertical position, because of gravity in the case of the 5 upper shutter 26 and because of the weights 25 in the case of the threshold shutter 18.

When it is desired to suspend the closing 10 functions of the shutters 18 and 26, and thus establish the ventilating function, the door 10 is first moved to open position, thus causing the shutter moving arms to move and hold the shutters to the horizontal position. Then the lever 36 is oscillated to apply draft 15 in opposite directions on the links 38, 39 and oscillate the latching bars 32, 35 toward the vertical center of the door and releasing them from the lugs 31 of the shutter moving arms. Thereafter the door 10 may be moved in either direction without affecting the 20 shutter moving arms or shutters, the shutter moving arms holding the shutters in the horizontal positions and the ventilating spaces at top and bottom of the door remaining open when the door is closed.

25 An opposite movement of the lever 36, when the door is open and in contact with the lugs 31, will reestablish the connection between the door and shutter-moving arms through the latching bars.

30 The threshold shutter 18 may in certain conditions be used independently of the upper shutter, or vice versa; and either shutter may be connected to the door independently of the other if desired.

35 I claim as my invention—

1. Ventilating means, comprising, in combination with a door mounted for oscillation in a frame, said door being spaced at its upper and lower margins from said 40 frame to provide ventilating spaces, shutters pivoted on transverse horizontal axes and adapted at times to close said ventilating spaces, and connections between said door and shutters for moving said shutters to horizontal position when the door is opened and to vertical closing position when the door is closed.

2. Ventilating means, comprising the combination with a door mounted for oscillation in a frame, said door being spaced at its upper and lower margins from said frame to provide ventilating spaces, of shutters pivoted on transverse horizontal axes and adapted at times to close said 55 ventilating spaces, and detachable connections between said door and shutters for moving the latter to horizontal position when the door is opened and to vertical closing position when the door is closed.

60 3. Ventilating means, comprising the combination with a door mounted for oscillation in a frame, said door being spaced at its upper and lower margins from said frame to provide ventilating spaces, of shut-

ters pivoted on transverse horizontal axes 65 and adapted at times to close said ventilating spaces, and detachable connections between said door and shutters for moving the latter to horizontal position when the door is opened and to vertical closing position 70 when the door is closed, said connections including means for maintaining the shutters in horizontal position when the connections are released.

4. Ventilating means, comprising the 75 combination with a door mounted for oscillation, said door being spaced at its lower margin from the floor to provide a ventilating space, of a movable threshold shutter hinged on a transverse horizontal axis 80 and adapted at times to close the space beneath said door, a shutter moving arm pivoted on a vertical axis and adapted at times to extend across and hold said shutter in horizontal position, and detachable connec- 85 tions between said door and arm.

5. Ventilating means, comprising the combination with a door mounted for oscillation and spaced at its lower margin from the floor to provide a ventilating space, of 90 a rigid threshold member, a movable threshold shutter hinged on a transverse horizontal axis to said rigid threshold, and adapted normally to close the space beneath said door, a shutter moving arm pivoted on said rigid threshold and adapted to engage and close said threshold shutter to horizontal position, and detachable connections between said door and arm.

6. Ventilating means, comprising the 100 combination with a door mounted for oscillation and spaced at its lower margin from the floor to provide a ventilating space, of a rigid threshold member, a movable threshold shutter hinged to said rigid mem- 105 ber and adapted to be in vertical position at times to close the space beneath said door, means normally acting to hold said shutter in such vertical closing position, an angular shutter moving arm pivoted on said rigid threshold and adapted to engage said shutter and move and hold it to horizontal position, said arm being formed with a lug adapted to engage the door on the opposite side from its pivot, and a latching bar 110 adapted to connect said lug to said door.

7. Ventilating means, comprising the combination with a door mounted for oscillation in a frame and spaced at its upper and lower margins from said frame to 120 provide ventilating spaces, of movable shutters hinged on transverse horizontal axes and adapted at times to close the said spaces, said shutters normally tending to remain in such vertical closing positions, 125 angular shutter moving arms pivotally mounted and adapted to engage said shutters when oscillated in one direction, to

move and hold said shutters to horizontal positions, said shutter moving arms being formed with members extending across the adjacent margins of the door and with lugs engaging the opposite side thereof, latching bars pivoted on said door and adapted to connect said lugs thereto, whereby said

arms are oscillated with the door, and means for conjunctively releasing said latching bars.

Signed at Mason City, in the county of Cerro Gordo and State of Iowa, this 17th day of August, 1918.

SETH A. WEIJMAN.
